UNITED STATES PATENT OFFICE.

WILLIAM W. RUMSEY, OF MILWAUKEE, WISCONSIN.

SAFETY LIGHT.

1,425,139.

Specification of Letters Patent. Patented Aug. 8, 1922.

Application filed February 28, 1921. Serial No. 448,335.

To all whom it may concern:

Be it known that I, WILLIAM W. RUMSEY, a citizen of the United States, residing at Milwaukee, county of Milwaukee, and State of Wisconsin, have invented a new and useful Improvement in Safety Lights, of which the following is a specification.

This invention relates to improvements in safety road signals.

- 10 It is an object of the invention to provide a safety device which will illuminate a portion of the street surface at night, and which, therefore, is particularly useful at street crossings or turns.
- 15 It is also an object of the invention to provide in combination with a visible signal, means suitable for protecting the signal against the impact of vehicles or the like, without, however, diminishing largely the strength of illumination, the vehicles themselves, however, being not endangered by the presence of the signal device in the street surface.

It is also an object of the invention to combine with a signal device of this character, means adjacent the device itself for actuating the signal or for interrupting the actuation.

With these and other objects in view, an embodiment of the invention is illustrated in the accompanying drawing, and described in the following specification.

In the drawing:

Fig. 1 is a perspective view of the signal safety device, and

Fig. 2 is an enlarged central section through the same.

A substantially circular casing 1 having an extension 2 is imbedded in the road' surface so as to project with its margin only over the level of the road. A circumferential flange 3 projecting from the inner wall of the casing inwardly serves as a support for an inverted glass cup 4, having a marginal flange 5, which rests upon the flange 3 of the casing. The thickness of the wall of the glass may be uniform in all parts of the same and may be sufficiently thin to permit the passage of the light rays through the same without decreasing the intensity of the light. The flange 5 resting on the flange 3 of the casing is covered by an annular packing, and a protector 7 preferably consisting of a casing and provided with a number of

radial perforations 8 is mounted on the margin of the casing 1 in spaced relation to the glass. The attachment of the protector 7 to the casing is effected preferably by a number of machine screws 9 which extend through the lower portion of the reflector and through a packing 10 into the top portion of the casing. The protector 7 also is provided adjacent each of these holding screws with a transverse slot 11 whereby the head of the screws may be suitably turned by means of a wrench or the like. The marginal portion of the protector has an off-set annular shoulder, part of the protector resting on the packing 6, and the other part being forced into engagement with the casing by means of the screws 9 which pass through the packing 10. Additional openings 12 may be disposed near the crown portion of the protector to emit the light in substantially vertical direction upwardly.

A source of light in the form of an incandescent light 13 or the like is secured centrally underneath the glass cup 4, the socket 14 being fastened to the bottom of the casing 1 by a plurality of holding screws 15. The conductors 16 lead from an extension 17 also supported by the bottom of the casing 1 to the lamp, and the extension 2 of the casing serves for receiving a handle 18 or some other actuating means connected by a link 19 with the switch handle 18.

It is obvious, therefore, that upon actuation of the lever 18 in the extension 2, the switch 17 may be thrown into on or off position, rendering each of these safety devices individually controllable.

The safety device can be manufactured at relatively low cost, can readily be installed, and can be kept clean so as not to be influenced by rain water or the like. Owing to the arrangement of the relatively heavy protector in spaced relation to the glass, the danger of breaking the glass of the cup 4 is entirely eliminated and the entire space between the top of the cup and the bottom of the casing is available for the insertion of a strong, high-powered, incandescent lamp or the like. The provision of a glass cup, the walls of which have uniform thickness, is also preferable, as compared with the provision of a lens made of relatively heavy glass, and in which the protection of the device against breakage is attained more

owing to the thickness of the glass of the lens than owing to the presence of a relatively heavy protector above the cup.

I claim:

- 5 1. In a roadway signal, the combination of a substantially circular base to be imbedded in a roadway, a substantially concavo-convex transparent dome supported upon said casing, a lighting device projecting into the cavity of said dome and a relatively heavy perforated protector of substantially the same contour of and embracing said dome, said protector being secured to the casing and engaging the peripheral margin of the dome for fixedly retaining the same upon said casing.
- 10 2. In a device of the character described, the combination of a substantially circular casing imbedded in the road, a signal device mounted in said casing, a protector projecting above the casing, and means secured to the casing and imbedded in the road for actuating or stopping the actuation of the signal device.
- 15 3. In a device of the character described, the combination of a substantially circular casing imbedded in the road, the casing having an annular flange, an inverted glass cup having an annular flange secured on said first named flange, a relatively heavy protector provided with symmetrically arranged openings, said protector being secured to the marginal portions of the casing, a signal lamp mounted on the bottom of the casing, a electric switch in said bottom, and means for operating said switch.
- 20 4. In a device of the character described, the combination of a substantially circular casing having an extension, a circular shoulder on the margin of the casing, a protector having a number of perforations and seated on the shoulder, a packing being interposed between said shoulder and said protector, head screws for securing said protector to said shoulder, the protector having a number of circumferential slits in which the heads of the screws are secured, a switch in the bottom of the casing, and actuating means for said switch located in the extension of the casing.
- 25 5. In a roadway signal, a base having a peripheral flange and imbedded in a roadway, a substantially concavo-convex transparent dome supported upon said flange, an illuminating means supported upon said base, and extending into said dome, a rigid guard of substantially semi-spherical dome shape arranged over and in spaced relation to the dome, and means for fixedly securing said dome and guard on said base.
- 30 6. In a roadway signal, a base imbedded in the roadway and having an upstanding peripheral flange, a substantially concavo-convex transparent dome supported upon said flange, illuminating means supported
- 35 substantially axially on said base and projecting into said dome with the center of light radiation above the lower edge of the dome, and a substantially semi-spherical dome-shaped guard arranged over and in spaced relation to the dome, and means for fixedly securing said guard to said flange.
- 40 7. In a roadway signal, a base imbedded in a roadway, a transparent concavo-convex dome supported by the base and projecting above the roadway, a source of light arranged within the dome, and a substantially semi-spherical concavo-convex guard carried by said base and spaced from said dome, said guard being provided with apertures of sufficient size to permit light from the source to emanate but of insufficient size to permit a vehicle wheel passing over the guard to reach said dome.
- 45 8. In a roadway signal, a circular base having a peripheral upstanding flange and adapted to be imbedded in a roadway, a substantially concavo-convex transparent dome supported above the level of the roadway on said flange, a similarly shaped rigid guard embracing the dome but in spaced relation thereto, an illuminating device on said base beneath the dome, a laterally disposed chamber on said base, and means in said chamber for controlling the illuminating device.
- 50 9. In a roadway signal, a base adapted to be imbedded in a roadway, a transparent dome supported on said base above the level of the roadway, a rigid guard for said dome, an electric illuminating device on said base within the dome, an electric switch on said base for controlling said illuminating device, and means on said base and imbedded in the roadway for manipulating said switch.
- 55 10. In a roadway signal, in combination, a base adapted to be imbedded in a roadway, a substantially concavo-convex transparent dome marginally supported upon said base and projecting above the roadway, an illuminating device on said base projecting into said dome and having the center of light radiation disposed above the peripheral margin of said dome, within the curved wall of the same and a substantially dome-shaped perforated guard projecting above the roadway and protecting said dome.
- 60 11. In a roadway signal, in combination, a base adapted to be imbedded in a roadway, a substantially concavo-convex transparent dome marginally supported upon said base and projecting above the roadway, and an illuminating device on said base projecting into said dome and having the center of light radiation disposed above the peripheral margin of said dome, within the confines of the curved wall of the same, and a guard for said dome and in spaced relation thereto.
- 65 12. In a roadway signal, in combination,

a base adapted to be imbedded in a roadway, a substantially concavo-convex transparent dome supported upon said base, and projecting above the roadway, a rigid protector 5 of substantially the same shape as said dome and lying above the latter and secured to said base and serving to secure said dome, said protector having a plurality of apertures therein, and an illuminating device on 10 said base projecting into said dome and having the center of light radiation disposed above the peripheral margins of said base and transparent dome.

13. In a roadway signal, the combination 15 with a base, of a transparent concavo-convex dome arranged above the roadway and having a marginal edge resting on said base, an illuminating means arranged within the cavity of the dome, and a substantially semi- 20 spherical concavo-convex rigid perforated guard projecting above the roadway, spaced

from and covering said dome, and fixedly secured to said base.

14. In a roadway signal, a substantially circular base adapted to be imbedded in a 25 roadway and provided with an annular flange and an annular shoulder above said flange, a transparent concavo-convex dome having an annular flange seating upon said base flange, a relatively heavy protector 30 overlying said dome and of substantially the same shape and provided with openings, said protector seating on said base annular shoulder and having an annular flange impinging upon the flange on said dome. 35

In testimony whereof, I affix my signature in the presence of two witnesses at 445 Milwaukee St., Milwaukee, Wisconsin.

WILLIAM W. RUMSEY.
